UNITED STATES PATENT OFFICE.

HEINRICH KOCK, OF HAMBURG, GERMANY.

STOVE FOR BURNING PETROLEUM.

SPECIFICATION forming part of Letters Patent No. 249,952, dated November 22, 1881.

Application filed October 1, 1881. (No model.)

To all whom it may concern:

Be it known that I, HEINRICH KOCK, of Hamburg, in the Empire of Germany, have invented certain new and useful Improvements in 5 Petroleum or Hydrocarbon Cooking and Heating Stoves, of which the following is a specification.

These improvements in petroleum or hydrocarbon stoves relate to the wick tubes or holders and to details of the construction of the outer casing.

In the accompanying drawings, Figure 1 represents a vertical section of a stove embodying my invention. Fig. 2 is a similar section 15 on a plane at right angles to that in which Fig. 1 is taken. Fig. 3 is a horizontal section on the line $x-x$, Fig. 1. Fig. 4 is a side view of one of the wick tubes or holders. Fig. 5 is an end view thereof, and Fig. 6 is a horizontal 20 section of one of the tubes or holders and a plan of the wick-feeders.

Similar letters of reference designate corresponding parts in all the figures.

The stove is constructed of several parts, 25 that are separable to permit of their being packed for transportation, and the principal parts are made of cast-iron, which is both cheap and strong.

A socket or stand, A, supports by lipped 30 edges a the reservoir or basin B, containing petroleum or hydrocarbon oil. Over said reservoir is arranged the cover-plate C, carrying the wick-feeders, burners, and wick-tubes. The body of the stove E encircles the burners, 35 over which is the outer and upper part or crown, F, of the stove-casing for carrying a kettle, boiler, or other object that has to be heated. This top part or crown F is movable vertically, and its bottom rim, e , has in it small grooves 40 or notches i , which fit upon ribs r , fastened or formed on the exterior of the body or casing E of the stove, and enables the crown to be lowered, as seen in Fig. 2. When the top part or crown, F, is raised, as in Fig. 1, the rim e becomes freed from the ribs r , and it can then 45 be turned for a short distance to make the rim rest upon the ribs, which will support the crown F in an elevated position. The purpose of this construction is to bring the crown, 50 and with it the boiler or other object that has to be heated, nearer to the flame or flames, or

to increase the distance from the flame, if required.

The body or case E of the stove is kept to the stand A by means of screws b , that pass 55 through lugs b' on the bottom part and catch over the lower projecting rim, b'' , of the body E. The top rim, E' , is attached to the body E by means of screws d , and prevents the crown F being fully drawn off from the body; 60 but when necessary to detach the crown from the body the rim E' can be removed and the crown lifted off said body.

Each burner—of which there may be two, or more or less, applied to each stove—consists 65 of a bottom casing, H, cast to the cover-plate C, and a top casing, H', that serves as wick holder or tube. The top casing, H', is hinged to the bottom casing at f , and can be turned backward to open the bottom casing, but is 70 held closed ordinarily by a screw, f' . The wick-tube of the casing H' is lined with tin-plate Z, or other smooth sheet metal, to make its inner part quite smooth, and to prevent 75 damaging of the wick when moved up or down in the cast-iron slot. The lining Z is secured at the top and bottom edges by folding it over the edges of the casing H'.

The wick-feeder for moving the wick up or down consists of a pair of rollers, $g-g$, connected 80 to each other by gear-wheels g' , and moved or turned in a well-known manner by one prolonged axle, g'' . The surface of the rollers forms part of the invention. Each roller is furnished with longitudinal grooves, and also circular grooves, by which a number of pyramidal teeth or sharp-pointed projections are formed on the outer circumference of each roller. The action of these rollers is to gripe and guide the wick on its whole breadth, while at the 85 same time the grooves allow the petroleum or other liquid to pass through the grooves along the whole breadth of the rollers from the basin or reservoir B freely to the top of the burner. This wick-feeder is not here claimed, 90 and may be made the subject of a future application for Letters Patent. The rollers $g-g$ rest in open bearings in the top edge of casing H, and the top casing, H', is turned over, while they are safely kept by top casing when the 95 latter is closed and fastened by the screw f' .

For extinguishing the flame each burner may

be furnished with a cap, *v*, pivoted so that it may be swung or partly rotated to cover or uncover the wick-tube *H'*. These caps *v* can be turned by rods *h*, which form prolongations of their pivots from outside the stove, and can be placed down to cover the flame. These caps may be constructed with an opening, *v'*, at the end or other part, so that when closed over the end of the wick-tube a small part of the flame remains uncovered and unextinguished. If the cap *v* is closed rapidly, the flame is extinguished altogether; but if the cap is carefully lowered down upon the flame, a small part of the wick will remain alight, and may be used for purposes where only little heat is required.

Instead of partly covering the wick, the flame may also be reduced in size by forming the upper or outer burner cap or cone, *R*, of each flame out of two parts, that can be narrowed or be drawn apart from each other for reducing or enlarging the width of the opening *t*, through which the flame passes.

What I claim as my invention, and desire to secure by Letters Patent, is—

25

1. In a petroleum or oil stove, the combination, with a wick-tube composed of cast metal, of a lining of tin or other sheet metal for giving said tube a smooth surface, substantially as specified.

30

2. In a petroleum or oil stove, the combination, with an outer case or body provided with vertical ribs, of a crown or top portion adapted to be supported on the upper ends of said ribs, and provided with notches, which, when said crown or top portion is turned, are adapted to fit over the ribs and allow the crown or top portion to be moved down, substantially as specified.

HEINRICH KOCK.
